UNITED STATES PATENT OFFICE.

HAROLD B. SMITH, OF WORCESTER, MASSACHUSETTS, ASSIGNOR TO WESTINGHOUSE ELECTRIC AND MANUFACTURING COMPANY, A CORPORATION OF PENNSYLVANIA.

HIGH-TENSION TRANSFORMER.

Application filed October 1, 1925. Serial No. 59,820.

My invention relates to electrical translating devices and particularly to high tension transformers.

One object of my invention is to provide 5 a high tension transformer, in which the formation of corona or incipient ionization potentials are prevented.

Another object of my invention is to provide 10 an electrical translating device of the oil-insulated type in which the deterioration of the insulating oil by reason of corona discharge is prevented.

It is also an object of my invention to provide 15 an electrical translating device for high tension service in which the several structural elements are all provided with curved surfaces, the respective radii of curvature of which are of such values that the concentration of corona forming or incipient ionization 20 potentials are avoided.

It is a further object of my invention to provide 25 an electrical transformer for high tension service in which the electromagnetic and electrostatic fields between the several windings of the transformer, the windings and the supporting structures, and the windings and ground are so distributed that the development of corona or incipient ionization forming potentials on any surface are 30 prevented.

It is a well-known fact that the insulating 35 values of oil in transformers, circuit breakers and the like deteriorates rapidly by reason of the presence of carbon, sludge, moisture and the like. Certain of the aforesaid deleterious agents are the products resulting from decomposition of a certain amount of the insulating oil itself. So far as I am now advised, no previous effort has ever 40 been made to improve operating conditions for such insulating oils at potentials that are capable of corona formation.

I have found that at certain voltages a 45 corona discharge occurs under oil in such apparatus with the result that a certain amount of the insulating oil is decomposed, thereby causing the accumulation of deleterious matter heretofore referred to. In addition to the decomposition of the insulating 50 oil, there is an actual deterioration of the insulating material employed in the transformer.

I propose to prevent the development of corona or incipient ionization forming potentials within the transformer by removing all 55 sharp edges from the several structural elements and by interposing such suitable shields in the electrostatic and electromagnetic fields that the potential gradient between the several shields shall not exceed 60 such corona forming or incipient ionizing values.

In electrical translating devices as heretofore constructed, it has been found that where distance alone was relied upon to provide 65 proper insulation between electrically charged bodies, even though the intervening spaces were filled with insulating material such as oil, impregnated insulating material, and the like, that, at the higher voltages, 70 such distances had to be increased in a ratio much greater than that directly proportional to the voltage increases.

The result of this need for increased spacing between the electrically charged bodies is such that very high potential transformers 75 relying upon insulation filled space alone for insulation are so cumbersome as to be virtually impossible of manufacture. I have found that by suitably arranging and controlling the potential gradients between the several elements of a transformer at differences of potential so that the potential gradient at any surface is kept below the corona or incipient ionization potentials, that I am 80 enabled to very greatly reduce the space required between the several elements at differences of potential over that hitherto necessary for the same voltages.

In the accompanying drawings, 90 Fig. 1 is an elevational view of a transformer embodying my invention.

Fig. 2 is a view, partially in elevation and partially in section, of the transformer shown in Fig. 1.

Fig. 3 is a curve showing the relation between the spacing of conducting members and applied voltages.

Fig. 4 is a fragmentary plan view of the transformer.

Fig. 5 is a sectional view of one side of the transformer windings.

Fig. 6 is a view, partially in elevation and partially in section, of a slight modification

of the transformer and showing the arrangement of the metallic shields about the distributing bushings, and

Fig. 7 is a similar view of a second modified form of my invention.

Fig. 8 is a diagrammatic plan view of another modified form of my invention.

Referring particularly to Figs. 1, 2 and 5, my invention comprises, in general, a transformer 1 disposed in a casing 2 and comprising a high tension winding 3 consisting of a plurality of coils 3a of pancake form disposed concentrically about a core member 4 and a low tension winding 5. The several coils 3a are provided at their outer edges with metallic potential and flux distributing members 6 of toroidal form, to certain of which are attached nested metallic shields 7 of annular form, for distributing the potential and flux fields generated within the transformer.

The upper coil 8 of the high-tension winding 3 differs from the pancake coils 3a in that it is formed by a plurality of turns of pipe formed into a spiral that also serves as a single protector by permitting discharge of excess local potentials between turns through the insulating medium. The upper contour of the entire coil 8 is curved so that no corona forming potentials may develop thereon.

The details of the structure associated with the distributing terminal 9, illustrated in Fig. 1, are shown in Fig. 6. The terminal 9 which is electrically connected to the outer terminal of the coil 8 extends upwardly through the casing 2. The several shields 7 have extensions 11 that are disposed in nested relation and also project upwardly and out of the casing 2 in parallel relation to the distributing terminal 9. The extensions 11 are severally connected externally of the casing 2 to horizontally extending portions 12 that terminate in toroidal potential and flux distributing members 13. The toroidal members 13 are accordingly disposed concentrically about the distributing terminal 9 in such manner that the potential gradient therefrom to the casing 2 is maintained at or below corona or incipient ionizing potentials.

The diameter of the several toroids 13 decreases successively outwardly from the terminal 9. The diameters of these successive toroidal members must be determined from a consideration of the limiting potential gradient at their surfaces to remain below the point of corona formation. This must be considered with reference to both the potentials between adjacent toroids and to the total potential of any one of them to earth. I have made use of toroidal members 13 whose diameters vary from three to nine inches for a transformer originally designed for generating 1,000,000 volts.

Referring particularly to Fig. 5, the terminal of the lowermost coil 3a is connected by a suitable conductor 14 to the casing 2 of

the transformer, thereby grounding that terminal of the high-tension winding 3. The several pancake coils 3a are connected directly to the upper coil 8 and the latter is connected to the distributing terminal 9, thereby placing the several coils 3a and the coil 8 in series connection between the terminals 9 and 14. The several coils 3a are separated from each other by suitable insulating bodies 15 of fuller board or the like. The inner and outer edges of certain or all of the coils 3 are provided with a toroidal distributor 6 in order to prevent the accumulation of corona forming potentials at the edges of the several coils 3a. The distributor 6 may, or may not, constitute the outer turn of the winding 3 as desired. Also, the distributor 6 may be omitted if desired.

Certain of the distributors 6 are attached to distributing shields 7 so disposed as to keep the potential gradients therebetween below corona forming potentials. The several shields 7 are of annular form, and, except for a small gap, extend entirely around the core member, one within the other, thereby providing the effect of toroids. The shields are provided with suitable openings 16 for permitting a circulation of the insulating fluid 17 therebetween. The upper surfaces of the annular shields 7 are provided with corrugations 18 constituting air traps and are provided with perforations 16.

In assembling the metallic shields 7 of the transformer shown in Figs. 1, 2 and 5, they are placed in position in sections. The annular portions of the several shields, together with their inwardly projecting bottom portions, are placed in position prior to the securing of the upper end or cover portions thereto.

The annular portion of the outermost shield is first placed in position and connected at its bottom portion to the outer turn of the corresponding coil. The annular portion of the adjacent shield is placed in position and connected to its corresponding coil in a similar manner. When all of the annular portions are in position, the end portions are then welded, or otherwise suitably secured, to the annular portions, the innermost shield being first completed and the end portions secured to the corresponding annular portions progressively outwardly.

Referring particularly to Fig. 3, there is shown a curve illustrating the distances ordinarily required between bodies at a difference of potential where insulation filled space is the main factor relied upon to insulate the bodies. At the voltage G a distance F will safely insulate these bodies and the curve between the points A and B is substantially a straight line. However, at a voltage D the corresponding point C required at insulating distance E that is not directly proportional to the voltage D and the distance F. This

curve clearly illustrates that there is for insulation filled space, a limit beyond which it is not economical to rely upon distance alone in insulating bodies between which there is a difference in potential. By the use of the combination of distributing toroids and shields, I am enabled to place bodies having a difference of potential materially closed together, than has heretofore been possible, by reason 10 of the elimination of corona or incipient ionizing potentials at any point within the transformer.

In Fig. 6, the arrangement of the shields differs from that of the transformer shown in 15 Figs. 1, 2 and 4 in that the annular portions 21 and the bottom portions 22 are in separate parts, each part being provided with a toroidal portion 23 that abut each other when the parts are assembled. In this arrangement, 20 the bottom portions 22 of the shields are placed in position successively, beginning with the lowermost one. The annular portions 21 are then placed in position in any desired order.

25 The extensions 11 of the metallic shields are assembled by placing the innermost extension in position adjacent to the corresponding annular portion of the shield and then placing the remaining extensions in 30 position progressively outwardly. The members 12 are then placed in position with respect to the corresponding extensions 11 by placing the lower-most member, or member of greatest diameter, in position and then proceeding progressively upwardly to assemble the remaining members.

The structure shown in Fig. 6 does not differ in principle from that shown in Figs. 1, 2 and 5, but this arrangement affords 40 considerable convenience in assembling the parts, as the necessity for electrically welding or otherwise connecting the adjacent edges of the parts of the members is avoided. The provision of the toroidal members 23 on the 45 adjacent edges of the parts of the shields avoids the concentration of potential or flux at these points and thereby prevents the formation of corona or incipient ionization.

50 Referring particularly to Fig. 7, I have shown a modification of the invention in which the terminal 9 passes through a materially larger opening 31 in the transformer casing 2 and the shields 32 terminate directly in toroids 33 that are disposed within the 55 casing 2 and that are distributed in progressively decreasing radii outwardly from the terminal in a manner similar to that of the modification shown in Fig. 6. In other particulars, these two forms of my invention are 60 similar.

Referring to Fig. 8, I have shown a form 65 of my invention in which a rectangular core member 31 has a low tension winding 32 disposed about each of its sides. The several

tween a source of electromotive force 33 and a ground connection 34.

Surrounding each of the low tension windings 32 are one or more metallic shields 35 that separate the low tension windings from 70 the coils 36 of a high tension winding. The several coils 36 of the high tension winding are each disposed in the form of a cylinder about one section of the core 31 and are separated from each other by one or more metallic 75 shields 35. The length of the several shields 35 and coils 36 decreases outwardly from the core 31 by reason of physical contact with the similar cylinders wound upon adjacent core sections, as is clearly shown in the drawing. At the points of contact between the several cylinders, toroidal distributors 37 are provided which engage each other and prevent accumulation of corona or incipient 80 ionizing potentials. The several coils and shields are connected in series relation between a ground conductor 38 and a distributor 39.

This form of my invention differs from the other forms only by its adaptation to a transformer having a rectangular core.

By means of the present invention, I have provided an electrical transformer that is characterized by the provision of suitable distributing toroids and shields that prevent the accumulation of corona forming or incipient ionizing potentials at any point within the transformer. By making the several radii of curvature proportional to the potential to 95 which the members are subjected, I am able to control the potential gradient at or near their surfaces in the desired manner. By eliminating the occurrence of corona forming or incipient ionizing potential gradients within the insulating medium of the transformer, I am able to prevent the deterioration 100 of the insulating medium and at the same time dispose my bodies having a difference in potential at distances from each other that are materially less than the limits heretofore existing in such devices. It is to be understood that such changes may be made in the structure and arrangement of the several parts as fall within the scope of the 105 110 115 120 125 130

I claim as my invention:

1. In a transformer, a core member, a low voltage winding associated therewith, a high voltage winding and a plurality of nested toroidal members associated with the high voltage winding and dividing it into sections.

2. In a transformer, a plurality of coils, insulating material disposed between adjacent coils, separate potential control and flux distributing means of annular form surrounding certain coils, and potential control and flux distributing shields electrically associated with certain of said distributing means.

3. In a transformer, a plurality of coils,

- insulating material disposed between adjacent coils, separate potential control and flux distributing means of annular form surrounding certain coils, and potential control and flux distributing shields electrically associated with certain of said distributing means.
4. In a transformer, a plurality of coils, insulating material disposed between adjacent coils, a separate potential control and flux distributing means surrounding each coil and potential control and flux distributing shields electrically associated with certain of said distributing means.
5. In a high potential winding, a plurality of coils disposed in vertical alinement, the end coil having a contour, the radius of curvature of which is such that the potential gradient at or near its surface is less than will 10 form corona or incipient ionization.
6. In a high potential winding, a plurality of coils disposed in vertical alinement, the end coil having a contour, the radius of curvature of which is such that the potential gradient at or near its surface is less than will 15 form corona or incipient ionization, said end coil comprising a helix of tubular conducting material.
7. In a high potential winding, a plurality of coils disposed in vertical alinement, a terminal coil having a contour, whose radius of curvature is such that the potential gradient at or near its surface is less than a corona or incipient ionizing potential, the 20 last-named coil comprising a continuous helix of conducting material.
8. In an electric translating device, a plurality of coils, an insulating fluid surrounding the coils, and nested potential control and 25 electric flux distributors of toroidal form attached to certain of the coils and immersed in the insulating fluid for the prevention of corona or incipient ionizing potentials in the insulating fluid.
9. In an electrical translating device, a plurality of space coils that are subjected to progressively increasing potentials in accordance with their spaced disposition, an insulating fluid surrounding the coils, and potential control and electric flux distributing means comprising a plurality of metallic shields of split annular form and distributors of toroidal form secured to certain of the coils and immersed in the insulating fluid, the 30 radii of curvature of the several toroids increasing in accordance with the progressive increase in potential of the several coils to which they are connected.
10. In an electrical translating device, a plurality of coils, an insulating fluid, surrounding the coils, and nested potential distributors of toroidal form attached to certain of the coils and immersed in the insulating fluid for the prevention of corona or incipient ionizing potentials in the insulating fluid.
11. In an electrical translating device, a plurality of coils, an insulating fluid surrounding the coils, and nested electric flux distributors of toroidal form attached to certain of the coils and immersed in the insulating fluid for the prevention of corona or incipient ionizing potentials in the insulating fluid.
12. In an electrical translating device, a plurality of coils, an insulating fluid surrounding the coils, and nested potential control and electric flux distributors of toroidal form attached to certain of the coils and immersed in the insulating fluid for the prevention of corona or incipient ionizing potentials in the insulating fluid, a terminal member for the device and nested potential control and electrical flux distributors of toroidal form surrounding the terminal member and in electrical connection with the first-named distributors.
13. In an electrical translating device, a plurality of coils, an insulating fluid surrounding the coils, and nested potential distributors of toroidal form attached to certain of the coils and immersed in the insulating fluid for the prevention of corona or incipient ionizing potentials in the insulating fluid, a terminal member for the device and nested potential distributors of toroidal form surrounding the terminal member and in electrical connection with the first-named distributors.
14. In an electrical translating device, a plurality of coils, an insulating fluid surrounding the coils, and nested electric flux distributors of toroidal form attached to certain of the coils and immersed in the insulating fluid for the prevention of corona or incipient ionizing potentials in the insulating fluid, a terminal member for the device and nested electric flux distributors of toroidal form surrounding the terminal member and in electrical connection with the first-named distributors.

In testimony whereof, I have hereunto subscribed my name this sixteenth day of September, 1925.

HAROLD B. SMITH.
